UNITED STATES PATENT OFFICE.

JAMES EMMETT BROWN AND EMMETT E. PETTIT, OF WAUKESHA,
WISCONSIN.

RAILWAY DRAFT APPLIANCE.

SPECIFICATION forming part of Letters Patent No. 586,160, dated July 13, 1897.

Application filed September 26, 1896. Serial No. 607,051. (No model.)

To all whom it may concern:

Be it known that we, JAMES EMMETT BROWN and EMMETT E. PETTIT, citizens of the United States, and residents of Waukesha, in the 5 county of Waukesha and State of Wisconsin, have invented certain new and useful Improvements in Railway Draft Appliances; and we do hereby declare that the following is a full, clear, and exact description thereof.

10 Our invention has for its object to prevent draw-bars of railway-cars from pulling out when breaks or disarrangement of parts in connection therewith occur, and a further object of said invention is to effect a maintenance of said draw-bars against longitudinal movement or vertical displacement after such breaks or disarrangement take place. These objects we attain by means of certain 15 peculiarities of construction and combination 20 of parts hereinafter specifically set forth with reference to the accompanying drawings, and subsequently claimed.

Figure 1 of the drawings is a longitudinally sectional view of a portion of a railway-car embodying our invention, this view being on the irregular plane indicated by line 1 1 in the succeeding figure, certain of the parts back of said plane being illustrated as partly broken away. Fig. 2 represents a transverse 30 section on the plane indicated by line 2 2 in the preceding figure.

Referring by letter to the drawings, A A represents the center sills; B B, the draft-timbers immediately under said sills; C, an 35 end sill, and D the dead-block at one end of a railway-car. At rest on a carry-iron E is a draw-bar F, this latter term being also applicable to the shank of a Master Car-Builders' coupling.

40 The shoulders b of the draw-bar are in opposition to inturned ends c of the yoke G that embraces the draft-spring H and its fol- lower-plates I, the latter being arranged to have their play intermediate of upper and 45 lower longitudinal guide-bars J in bolt con- nection with brackets K on the inner sides of the draft-timbers B, above specified.

The construction and arrangement of parts thus far described is common in the con- 50 struction of railway-cars, and the essential features of our invention are subsequently

described in connection therewith, this invention being also applicable in connection with old or new draw-bars, and also to the latter in various forms known to the art. 55 The showing herein made applies to a new draw-bar of one well-known form; but certain variations of construction by which our invention may be applied to an old draw-bar of similar form or to new and old draw-bars 60 of other forms are matters of mechanical expediency that do not affect said invention in a generic sense.

As herein shown, longitudinal slots in the yoke-straps and draw-bar may take the place 65 of the usual bolt-holes and be engaged by the vertical shank L of a buffer-head M, that comes to rest on the upper strap of the yoke, the lower end of the head-shank being preferably provided with slots in the direction of 70 its length for the engagement of taper keys N, driven in opposite directions below the lower strap of said yoke and having their narrowest ends slightly bent to prevent automatic displacement. 75

The front face of the buffer-head M is vertical and of sufficient area to have ample bearing against the inner face of the end sill when brought into contact therewith, as hereinafter set forth, and projecting from said 80 front face of the buffer-head is a spur P, that is preferably in the form of the upper half of a cone, this spur being forced into said end sill at the same time the aforesaid buffer-head is brought into contact therewith. The 85 rear face of the buffer-head is preferably curvilinear, and the sides of said head are vertical and parallel to the center sills above specified.

In rear of the buffer-head a transverse block 90 of wood Q is preferably connected to the center sill by mortise-and-tenon joints and stay-bolts; but when it is not convenient to make said joints the block may have bolt connection with the end sill and dead-block in ad- 95 dition to its like connection with said center sill, the longitudinal bolts serving to com- pensate for the buffing strain that may come upon said block, as hereinafter set forth.

The means for holding the block Q in place 100 and compensating for buffing strain thereon are matters of mechanical expediency not

affecting the function of said block. Hence it has not been deemed necessary to fully illustrate either of the above-described possible means for that purpose.

5 Eyebolts R in connection with the block Q are engaged by trunnions d, that extend from the rear end of a dog S in the form of a cast-metal shell normally at rest on the top of the buffer-head M, the forward end of the dog 10 being of a contour corresponding to that of the rear face of said head. Inasmuch as the buffer-head M has play along the horizontal inner face of the dog S incidental to reciprocation of the draw-bar under ordinary conditions 15 the rear portion of this under or friction face of said dog is preferably recessed to prevent formation of a shoulder as the result of wear. The sides of the dog strengthen the latter, and being normally in opposition to the sides 20 of the buffer-head lateral play of said dog is thus limited.

In case of a break or disarrangement of parts that would ordinarily permit the draw-bar to pull out, the buffer-head M will come 25 in contact with the end sill of the car and the spur P projecting from the front face of said head will be caused to pierce the wood-fibers and thus automatically embed itself in said sill to prevent vertical displacement of 30 said draw-bar. At the same time sufficient clearance will be had to permit of the dog S dropping behind the buffer-head and thus prevent rearward movement of the draw-bar. Hence it will be seen that the latter is not 35 only held against vertical displacement; but that it is also prevented from longitudinal movement incidental to pull or push thereon, the rear end of said dog being then flush with and against the block Q, set in between the 40 center sills of the car. The above result having been accomplished the draw-bar is automatically locked in place and will remain serviceable for an indefinite period pending such repairs as may be necessary.

45 While we have shown the buffer-head provided with a depending shank engaging longitudinal slots in the yoke and draw-bar, together with keys engaging the shank below said yoke, it is practical in connection with 50 a spindle draw-bar to proportion said shank so as to obtain clearance for the spindle-head and to also provide its lower end with a thread for a nut and lock-nut. It is also practical to do away with the shank and have 55 the buffer-head in bolt or rivet connection with the upper strap of the yoke herein shown or the upper side of a spindle draw-bar. These variations being matters of mechanical expediency that would readily suggest themselves to car-builders and repairers, their illustration has not been deemed necessary, inasmuch as they do not in any way affect what we consider is our invention in its generic sense.

60 Having now fully described our invention, what we claim as new, and desire to secure by Letters Patent, is—

1. The combination of a draw-bar, a buffer-head movable with the same in rear of a railway-car end sill, a spur extending forward 70 from the buffer-head to be forced into the end sill in case of break or disarrangement of parts that would ordinarily permit the draw-bar to pull out of place, and suitable means for automatically preventing rearward movement of said draw-bar should an engagement of the spur with said end sill be effected.

2. The combination of a draw-bar, a buffer-head movable with the same in rear of a railway-car end sill, a spur in the form of the 80 upper half of a cone extending forward from the buffer-head to be forced into the end sill in case of break or disarrangement of parts that would ordinarily permit the draw-bar to pull out of place, and suitable means for preventing rearward movement of said draw-bar 85 should an engagement of the spur with the end sill be effected.

3. The combination of a draw-bar, a buffer-head movable with the draw-bar in rear 90 of an end sill constituting part of a railway-car provided with said draw-bar, and a drop-dog that is normally supported on the buffer-head but which automatically comes in rear of the same when the aforesaid draw-bar tends 95 to pull out of place.

4. The combination of a draw-bar, a buffer-head movable with the draw-bar in rear of an end sill constituting part of a railway-car provided with said draw-bar, a block supported intermediate of center sills pertaining to the car, and a dog in hinge connection with the block, this dog being normally supported on the buffer-head but having automatic descent in rear of the same in case the aforesaid draw-bar tends to pull out of place.

5. The buffer-head having a depending shank engageable with a draw-bar in rear of an end sill constituting part of a railway-car, a spur extending forward from the buffer-head, and a drop-dog that automatically finds its way in rear of said buffer-head in case the spur of the same is engaged with the end sill.

6. The buffer-head having a depending shank engageable with a draw-bar in rear of an end sill constituting part of a railway-car, and a drop-dog normally supported on the buffer-head but which automatically comes in rear of the same when said draw-bar tends to pull out of place.

7. The buffer-head having a depending shank engageable with a draw-bar in rear of an end sill constituting part of a railway-car, a spur extending forward from the buffer-head, and a drop-dog normally supported on 125 said buffer-head but which automatically comes in rear of the same when said draw-bar tends to pull out of place.

8. The combination of a draw-bar, a yoke having inturned ends in opposition to draw-bar shoulders, a draft-spring and its follower-plates embraced by the yoke in rear of the draw-bar, a buffer-head that rests on the yoke but is provided with a vertical shank that

engages longitudinal slots in said yoke and draw-bar, and keys engaging apertures in the buffer-head shank below the aforesaid yoke.

9. The combination of a draw-bar, a yoke engaged therewith, a buffer-head having a depending shank engaging longitudinal slots in the yoke and draw-bar, keys engaging apertures in the buffer-head shank below said yoke, a spur extending forward from said buffer-head, a block arranged between center sills of the car, and a dog in hinge connection with the block, this dog being normally supported by the aforesaid buffer-head but having automatic descent in rear of the same in case the aforesaid draw-bar tends to pull out of place.

10. The combination of a draw-bar, a buffer-head movable with the draw-bar in rear

of an end sill constituting part of a railway-car provided with said draw-bar, and a drop-dog that is normally supported on the buffer-head and provided with a recess in rear of that portion having contact with said buffer-head, this dog being automatically positioned in rear of the aforesaid buffer-head when the aforesaid draw-bar tends to pull out of place.

20
25
In testimony that we claim the foregoing we have hereunto set out hands, at Waukesha, in the county of Waukesha and State of Wisconsin, in the presence of two witnesses.
